UNITED STATES PATENT OFFICE.

LOGAN N. KELLEY, OF NEW YORK, N. Y., ASSIGNOR TO CHARLES E. STADE, OF NEW YORK, N. Y.

FLUID VACUUM FEED DEVICE.

Application filed August 18, 1920. Serial No. 404,443.

To all whom it may concern:

Be it known that I, LOGAN N. KELLEY, a citizen of the United States, residing in New York, in the county of New York and 5 State of New York, have invented certain new and useful Improvements in Fluid Vacuum Feed Devices, of which the following is a specification.

My present invention relates to an improvement in vacuum fluid feed control mechanisms for motor vehicles, motor boats and the like.

One object of my invention is to provide a vacuum fluid feed control mechanism 10 which shall be simple in construction, and reliable in operation, and of extremely compact form.

Another object is to provide a vacuum fluid feed control mechanism having means 15 for viewing the interior of the device for determining the amount of fluid therein and the action of the parts thereof.

Another object is to provide a vacuum feed control mechanism which may be located on or adjacent to the dash of the motor vehicle in plain sight of the operator, and which has means for viewing the interior of the device for determining the amount of fuel therein without lifting the 20 hood of the engine, and to confirm the proper action of the control mechanism and the flow of the fuel.

A feature of my device is the use of an oscillatable valve having oppositely disposed closure means for sequentially opening and closing the valve ports.

Another feature of my device is the use of a valve oscillatable by float means and having oppositely disposed closure means 25 for sequentially opening and closing the valve ports.

Another feature of my device is the use of a valve having oppositely disposed closure means for sequentially opening and closing the valve ports, the valve being oscillatable by a float arranged for imparting a starting movement or jar to the valve for facilitating the oscillation of the valve by the float.

Another feature of my device is the use of a valve having oppositely disposed closure means for sequentially opening and closing the valve ports and oscillatable by a float, the valve having stop means for engagement therewith of means actuated by

the float for oscillating the valve to open or to close sequentially the valve ports by movement of the float.

Another important feature of my device is the few and simple operative parts 60 whereby the ports are sequentially opened or closed to admit fuel or to stop the flow thereof to the container.

These, and other objects, features and capabilities of my invention will be disclosed in the course of the following description.

In the accompanying drawings which form part of this specification, Figure 1, is a side elevation of my device with the side 70 casing removed.

Figure 2, is an end elevation of my device with the end casing partly broken away.

Figure 3, is a fragmental view showing the 75 valve mechanism.

Figure 3^a, is a view, similar to Fig. 3, showing by dotted lines the float in two positions for indicating the movement of the float irrespective of the valve, and showing the means, or bent arm, actuated by the float, 80 in two positions of contact with the stop means on the valve, for oscillating the valve by movement of the float.

Similar letters or numerals refer to similar parts throughout the several views.

The embodiment of my invention shown in the drawings comprises a tank generally denoted by A, having a main compartment B and a secondary compartment C.

The cover or top 10 of the compartment B 90 is removably attached to the sides of the tank A as by the screws 11 engaging the side extensions 12. The cover or top 10 has on the exterior thereof, preferably cast thereon, apertured lugs 13, 14 and 15, and has on 95 the interior thereof arranged in alinement with the lugs 14 and 15, and preferably cast on the cover or top 10, an inwardly extending bracket 16. The lug 13 has a threaded exterior for engagement therewith of a nut 100 17 for operatively connecting to the lug 13 a pipe 18 communicating with the source of fluid supply, the aperture 19 of the lug 13 registering with a passage 20 through the cover or top 10.

The lug 14 has a threaded interior which communicates by the passage 21 through the cover or top 10 with the suction bore or suction port 22 in the bracket 16, which suction bore or suction port opens into the interior 110

of the main compartment B, the bracket 16 also being provided with an atmosphere bore or port later mentioned, the plane face of the bracket having said bores or ports there-
5 through constituting a valve section.

The pipe 23 which communicates with the intake manifold of an internal combustion engine E, is received in the threaded interior of the lug 14.

10 The apertured lug 15 is open to the atmosphere and communicates through a passage 24 in the cover or top 10 with the atmosphere bore or port 25 before mentioned in the bracket 16, which atmosphere bore or
15 port opens into the interior of the main compartment B.

The lug 15 has an extension or shoulder 26 having the bore 27 therein which communicates through a passage 28 in the cover or top 10 with an aperture 29 in the extended end of the bracket 16, the atmosphere pipe 30 being received in the aperture 29 and extending through the bottom 31 of the compartment B into the secondary compartment C.

18 The pin 32 is pivoted in the bracket 16, being held in place by the nut 33, and is provided at its end opposite to the bracket 16 with a head 34, which preferably is integral
30 with the pin 32.

The valve disk or plate 35 preferably is of the segmental shape shown and is provided with a cut out space or bridged portion 36 having a solid surface portion 37 adjacent to one side thereof and a solid surface portion 38 adjacent to the other side thereof.

24 The valve disk or plate 35 is loosely mounted on the pin 32 adjacent to the inner face of the bracket 16, and is provided with oppositely disposed lugs or stops 39 and 40, the lug or stop 40 having a threaded hole for receiving therein an adjustable screw 41 extending transversely to the lugs or stops 39 and 40 and limiting or filling in the space between these lugs or stops. The helix spring 42 is arranged around the pin 32, one end thereof being seated in the pin 32 and the other end being seated in the valve disk or plate 35, the spring 42 serving to hold the valve disk or plate 35 in position adjacent to the bracket 16, for opening or closing in prearranged sequence the suction port 22 and atmosphere port 25 of the bracket.

28 The bail arm 43 preferably is integral with the head 34 of the pin 32 and carries the bail 44 in which is swung the float 45. But it is obvious that the bail arm 43 could as well be extended as an arm fixedly secured to the float 45, the bail 44 being omitted, and the float 45 carried directly by this arm.

The valve disk actuating finger 46 extends from the head 34 on the side thereof opposite to the bail arm 43, and substantially in line therewith, and is provided

with a transversely bent end 47, parallel to the pin 32, the end 47 being located between the lug 39 of the valve disk or plate 35 and the inner end of the adjustable screw 41, and being engageable with the lug 39 or the screw 41 when oscillated or moved by the rising or falling of the float 45.

The bottom 31 of the main compartment B slopes inwardly to its central or middle point, and at such central or middle point 75 is provided with a passage 48, with which the pipe 49 is connected.

The pipe 49 has an upturned end 50 provided with a hinged cover or valve 51, movable to open position by pressure upon its 80 under side.

The bottom 52 of the secondary compartment C is removably attached to the sides of the tank or container A as by screws 53 engaging the side extensions 54, the bottom 85 52 being provided with a suitable outlet such as 55 to the carburetter of the internal combustion engine, and provided with a suitable drain such as 56.

The side of the main compartment B is 90 provided with an opening or window 57, covered by glass or other suitable transparent material, and so arranged as to permit a view therethrough of the float 43, when the float is in either its uppermost or lowermost 95 position.

In operation, the float 45 being in its lowermost position, as can be readily seen by means of the window 56, the bent end 47 of the finger 46 is in engagement or contact 100 with the lug or stop 39 of the valve disk or plate 35, and the suction port or bore 22 of the bracket 16 is exposed by the cut out or bridged portion 36 of the valve disk or plate 35, the atmosphere port or bore 25 being 105 covered or closed by the solid surface portion 38. Operation of the engine E exhausts by means of the pipe 23, the air from the compartment B by means of the port or bore 22, thereby causing an indrawing or 110 flow of fluid into the compartment B by means of the pipe 18 from the source of supply.

Due to inflow of fluid the float 45 is raised from its lowermost position, until by upward movement of the float the bent end 47 of the finger 46 releases its contact or engagement with the lug or stop 39 of the valve disk or plate 35, and oscillates or swings into contact with the adjustable screw 41, thereby oscillating or moving the valve disk or plate 35, so that the solid surface portion 37 covers or closes the suction port or bore 22 and the atmosphere port or bore 25 is opened or exposed by the cut out or bridged portion 36. 125 The admission of atmospheric air pressures through the port or bore 25 into the compartment B permits the fluid to flow into compartment C through the pipe 49 and valve 51, the atmosphere pipe 30 being always 130

open, thereby venting the compartment C, and the fluid being conducted by the outlet 54 to the carburettor of the engine. As the float 45 is lowered, due to outflow of the 5 fluid from the compartment B, the bent end 47 of the finger 46 releases its contact with the adjustable screw 41 and oscillates or swings into contact with the lug or stop 39, thereby moving the valve disk or plate 35 to 10 cover the atmosphere port or bore 25 and to open the suction port or bore 22, or to the first described position. The inertia of the float 45 tends to bring the bent finger-end 47 into contact with the lug or stop 39 or 15 the screw 41, as the case may be, with sufficient jarring effect to prevent sticking of the valve disk or plate 35 in its movements, and the screw 41 is adjustable for regulating the distance of the swing of the bent finger-end 20 47 for contact with the lug or stop 39 or with the screw 41, to give the desired impacting force to the bent finger-end 47.

Having thus described my invention it should be understood that there may be 25 modifications thereof and variations therein without departing from the spirit of the invention or exceeding the scope of the appended claims.

Having thus described my invention, I 30 claim:

1. A vacuum fluid feed control mechanism comprising, with an internal combustion engine having an intake manifold and having a carburettor, a tank comprising a main 35 compartment and a secondary compartment, the main compartment having a bracket provided with air exhaust and air intake ports, the air exhaust ports communicating with said carburettor, means for admitting fluid to the main compartment, means for passage of fluid from the main compartment to the secondary compartment, said means comprising a valve normally closed and movable to open position by pressure 40 of fluid from the main compartment, means for communication of the secondary compartment with the atmosphere, means for outlet of fluid from the secondary compartment communicating with said carburettor, an oscillatable valve pivotally connected to 45 said bracket and having oppositely disposed closure means for sequentially opening and closing said air exhaust and air intake ports, and having oppositely disposed stops, and a 50 float pivotally connected to said bracket for oscillating said valve by rise and fall of the float with the fluid in said main compartment and provided with means for sequentially engaging said stops of the oscillatable 55 valve.

2. In combination, a float compartment having a valved exit; a bracket in said float compartment provided with a flat face 60 provided with suction and atmospheric ports; a pin pivoted in said bracket and having a

head; an arm extending from said head and pivotally movable therewith; a bail pivotally connected to said arm; a valve plate loosely mounted on said pin in contact with said face for covering one or the other of said ports; a pair of oppositely disposed lugs on the valve plate; an actuating finger on said head and engaging in said space between said lugs; and a float swung in said bail. 75

3. In combination, a float compartment having a valved outlet; a bracket in said float compartment provided with a flat face provided at opposite side portions with suction and atmospheric ports extending 80 through the top of the tank; a pin pivoted in said bracket and having a head; an arm extending from said head and pivotally movable therewith; a bail pivotally connected to said arm; a valve plate loosely 85 mounted on said pin for covering one or the other of said ports; a pair of oppositely disposed lugs on the valve plate; a set-screw in one of said lugs for adjustably limiting the space between the lugs; an actuating finger on said head and engaging in said space between said lugs; and a float swung in said bail. 90

4. In a vacuum feed control mechanism, the combination of a fluid receiving tank, a 95 bracket in said tank provided with a suction port and an atmospheric port, an oscillatable valve connected to said bracket and having means for sequentially opening and closing said suction and atmospheric ports and having oppositely disposed stops, a float, and means cooperating between the float and said bracket for pivotally supporting the float and provided with means for sequentially engaging said stops when the float 100 rises or falls.

5. In a vacuum feed control mechanism, the combination of a fluid receiving tank, a bracket in said tank provided with a suction port and an atmospheric port, an oscillatable 110 valve connected to said bracket and having means for sequentially opening and closing said suction and atmospheric ports and having oppositely disposed stops, adjustable means for limiting the space between said 115 stops, a float, and means cooperating between the float and said bracket for pivotally supporting the float and provided with means for sequentially engaging said stops when the float rises and falls. 120

6. In a vacuum feed control mechanism, the combination of a fluid receiving tank, a flat faced bracket in said tank having a suction port and an atmospheric port, a flat plate connected to the bracket for oscillatory 125 movement and comprising oppositely disposed solid portions for covering said ports and an opening between the solid portions for uncovering said ports and having oppositely disposed stops on one of the solid 130

- portions, and a float connected to said bracket by means comprising a pivotally movable arm having a finger for sequentially engaging said stops when the float rises and falls.
- 5 7. In a vacuum feed control mechanism, the combination of a fluid receiving tank, a flat faced bracket in said tank having a suction port and an atmospheric port, a flat plate connected to the bracket for oscillatory
- 10 movement and comprising oppositely disposed solid portions for covering said ports and an opening between the solid portions for uncovering said ports and having op-

positely disposed stops on one of the solid portions, a float connected to said bracket 15 by means comprising a pivotally movable arm having a finger for sequentially engaging said stops when the float rises or falls, and a set screw appurtenant to one of said stops for limiting the path of movement of 20 said finger between the stops.

LOGAN N. KELLEY.
